ADJUSTABLE BARBER SHEAR

Clyde H. Turbett, Harrisburg, Pa., assignor of one-half to Jacob A. Coulson, Borough of Carlisle, Pa.

Application September 26, 1952, Serial No. 311,727

3 Claims. (Cl. 30—210)

This invention relates to hair clippers of the adjustable type, and in particular a clipper in which cutting elements extend from the end of a handle and in which a lower clipper plate is laterally adjustable in relation to a reciprocating clipper plate whereby the device is readily adjustable to cut hair to different lengths.

The purpose of this invention is to provide an adjustable hair clipper wherein the relative positions of the clipper plates are adjustable as the clipper is used.

Various types of attachments have been used in combination with hair clippers to facilitate grading or graduating the hair, however, such devices have not been successful because they interfere with the conventional operation of the clipper. With this thought in mind, this invention contemplates an adjustable hair clipper wherein clipper plates extended from the end of a handle are readily adjusted by a thumb screw on one side of the handle so that the parts may be adjusted to cut hair at different lengths as the cutting progresses.

The object of this invention is, therefore, to provide means for mounting clipper plates in a handle whereby one plate is readily adjustable in relation to another to regulate the length of hair cut by the clipper.

Another object of the invention is to provide an improved hair clipper in which the cutting elements are adjustable and wherein the adjusting means does not interfere with conventional operation of the clipper.

A further object of the invention is to provide a hair clipper having adjustable clipper plates extended from the end of a handle in which the clipper is of a comparatively simple and economical construction.

With these and other objects and advantages in view the invention embodies a handle having reciprocating means therein, a lower clipper plate mounted for lateral movement in the handle, a thumb screw for adjusting the position of the lower clipper plate, an upper clipper plate slidably mounted on the lower clipper plate and operatively connected to said reciprocating means in the handle and a spring guard mounted in the handle and extended over said upper clipper plate for retaining the upper clipper plate in cutting relation to the lower clipper plate.

Other features and advantages of the invention will appear from the following description taken in connection with the drawing, wherein:

Figure 1 is a sectional plan through the improved hair clipper with parts of the clipping elements shown at elevation.

Figure 2 is a side elevational view of the improved hair clipper taken on line 2—2 of Figure 1 and with the clipper plates and mounting parts of the clipper shown in section.

Figure 3 is a cross section through the handle of the clipper taken on line 3—3 of Figure 1.

Figure 4 is also a section through the handle of the clipper taken on line 4—4 of Figure 1.

Figure 5 is a similar section through the handle taken on line 5—5 of Figure 1.

2

Figure 6 is a detail showing an end elevational view of the clipper plates with a spring guard positioned over the plates shown in section.

Figure 7 is a plan view showing the lower clipper plate.

Figure 8 is a similar view showing the upper clipper plate.

Figure 9 is a detail showing a portion of the lower clipper plate with parts thereof broken away showing a threaded opening therethrough.

Figure 10 illustrates a plurality of sections taken on line 10—10 of Figure 1 through the clipper plates and showing the plates in different adjusted positions.

Referring now to the drawing wherein like reference characters denote corresponding parts the improved adjustable barber's shear of this invention includes a lower stationary, though laterally adjustable clipper plate 10, an upper reciprocable clipper plate 11, a spring element 12 having slots 40 providing a guide for the upper clipper plate, an adjusting screw 13, a handle 14 in which the parts are mounted, a motor including a solenoid 15 and a core plate 16, and a bell crank 17 for operatively connecting the motor to the reciprocating upper clipper plate 11.

The lower clipper plate 10 is provided with comb or cutting teeth 18 and 19 in opposite edges, a transversely disposed bar 20 having a slot 21 therein at the outer end in which an end 22 of said element guide 12 is positioned, extensions 23 and 24 at the opposite ends of the comb teeth, transversely positioned bars 25 and 26, and a transverse threaded opening 27 in which the adjusting screw 13 is threaded.

The bar 25 of the lower clipper plate 10 is positioned to slide laterally in the handle 14, the bar being positioned in a transversely disposed groove 28 provided in the interior of the lower side of the handle, and the bar 26 is positioned in a similar groove 29 also provided in the lower side of the handle.

The upper clipper plate 11, which is provided with an offset end 30 on which a pin 31 that extends into a yoke 32 of the bell crank 17 is positioned, is also provided with cutting teeth 33 and 34, with a bar 35 at the outer end and with projections 36 and 37 at the inner ends of the teeth. The clipper plate 11 is also provided with spaced pins 38 and 39 that are positioned to extend into elongated slots 40 and 41 in the spring guide 12 and, as the clipper is reciprocated by the motor, the pins travel longitudinally in the slots thus retaining the upper clipper plate in fixed relation to the center line of the handle.

The spring guide 12 is provided with a substantially U-shaped section 42 at its inner end, and said guide is secured in position by screws 43 and 44, that extend through flanges 45 and 46 which extend from the section 42.

The guide 12 is provided with an upwardly bowed section 47 that is positioned to be engaged by an adjusting screw 48 whereby tension against the upper clipper plate is adjustable. The upper clipper plate is also provided with a recess 49, in the under surface whereby the points of contact of the upper clipper plate with the lower clipper plate are at the sides of the plates.

The bell crank 17 is mounted by a spring 50 on one end of a bracket 510 in which the solenoid 15 of the motor is mounted and with the bell crank 17 mounted in this manner the yoke 32 will reciprocate the upper clipper plate as the core plate 16, which may be formed of iron or the like, is drawn toward the core of the solenoid and released, by conventional means. The current is supplied to the motor with wires 51 and 52 of a cable 53 that extends through an opening in a head 54 at the end of the handle.

With the parts formed in this manner current supplied to the motor in the handle of the shear actuates the crank

17 whereby the upper clipper plate is reciprocated longitudinally of the lower clipper plate and to change the number of hairs cut by the clipper the lower clipper plate is moved laterally by the adjusting screw 13 whereby hair may be cut comparatively close to the scalp such as with a "triple-O clipper," and with one side of the clipper set to cut the hair close to the scalp the opposite side is set to cut hair further from the scalp.

The device is adapted to be adjusted whereby short or long hair may be cut by either side so that the device is adapted to be used by either a right hand or a left hand barber.

The handle 14 is provided with a removable base 55 which is attached to the handle with screws 56, and, as illustrated in Figures 2 and 3, the clipper plates are mounted on the base. The base is provided with a projection 57 at one side that forms a bearing for the adjusting screw 13, and a collar 58, positioned at the inner end of the bearing 57 retains the screw in position. With the screw extended through the threaded opening 27 of the lower clipper plate the plate is readily adjusted laterally, and when it is desired to remove the lower clipper plate the screw is rotated until the plate runs off of the end of the screw.

The clipper plates extend through a slot 59 in the end of the handle and the end surfaces 60 and 61 of the extensions 23 and 24 are positioned to contact the end of the handle whereby the ends of the slot 59 are closed.

It will be understood that modifications, within the scope of the appended claims, may be made in the design and arrangement of the parts of the device without departing from the spirit of the invention.

What is claimed is:

1. A hair clipper comprising a handle, a lower clipper plate having teeth in the edges thereof extended from one end of the handle, an upper clipper plate having teeth in the edges thereof extended from said end and positioned to slide longitudinally on said lower clipper plate whereby the teeth thereof coact with the teeth of the lower clipper plate for shearing, means for retaining the upper clipper plate in alignment with said handle, means adjusting said lower clipper plate, a motor in said handle, and means operatively connecting said motor to the upper clipper plate for longitudinally reciprocating said upper clipper plate on the lower clipper plate, said means

for retaining the upper clipper plate in alignment with the handle also providing means for resiliently urging said upper clipper plate against the lower clipper plate.

2. In a hair clipper, the combination which comprises 5 a handle, a lower clipper plate mounted to slide laterally in said handle and extended from one end thereof, an adjusting screw in the handle for adjusting the position of said lower clipper plate laterally in the handle, an upper clipper plate mounted to reciprocate longitudinally on said lower clipper plate, a motor in the handle, means operatively connecting the motor to said upper clipper plate, a spring guide mounted in the handle and extended over said upper clipper plate, means connecting said upper clipper plate to said spring guide for retaining the upper clipper plate in alignment with the handle, said spring guide being shaped to resiliently urge the upper clipper plate against the lower clipper plate, and means for adjusting the tension of said spring guide.

3. In a hair clipper, the combination which comprises 20 a handle, a lower clipper plate mounted to slide laterally in said handle and extended from one end thereof, an adjusting screw in the handle for adjusting the position of said lower clipper plate laterally in the handle, an upper clipper plate mounted to reciprocate longitudinally on said lower clipper plate, a motor in the handle, means operatively connecting the motor to said upper clipper plate, a spring guide mounted in the handle and extended over said upper clipper plate, means connecting said upper clipper plate to said spring guide for retaining the upper clipper plate in alignment with the handle, said spring guide being shaped to resiliently urge the upper clipper plate against the lower clipper plate, and means for adjusting the tension of said spring guide, said lower clipper plate having a transversely disposed slot in the extended end and said spring guide having a portion on the end extended into the said slot in the end of the lower clipper plate.
